UNITED STATES PATENT OFFICE.

GEORGE S. GATCHELL, OF ROSELLE PARK, NEW JERSEY, ASSIGNOR TO THE SINGER
MANUFACTURING COMPANY, A CORPORATION OF NEW JERSEY.

MULTIPLE-NEEDLE SEWING MACHINE.

1,410,057.

Specification of Letters Patent. Patented Mar. 21, 1922.

Application filed August 10, 1917. Serial No. 185,446.

To all whom it may concern:

Be it known that I, GEORGE S. GATCHELL, a citizen of the United States, residing at Roselle Park, in the county of Union and

5 State of New Jersey, have invented certain new and useful Improvements in Multiple-Needle Sewing Machines, of which the following is a specification, reference being had therein to the accompanying drawings.

10 This invention relates to improvements in multiple needle sewing machines of the type disclosed in the application of G. E. Molyneux and G. S. Gatschell, Series No. 40,564, filed July 19, 1915, and has for an object the

15 improvement of the thread-controlling mechanism of the machine disclosed therein to overcome the noise and speed-limitation incident to the use of cam-actuated and spring-controlled thread-engaging levers,

20 and to prevent skipping of stitches or thread-breakage due to abnormal displacement or bunching of the needle-loops on the looper, thereby rendering the machine quiet, smooth-running, and efficient under high-speed operating conditions.

A further object of the invention is to provide the machine with improved differential feeding mechanism wherein the stroke of the fulling feed-member may be readily

25 adjusted while the machine is in operation to suit the character of the work being stitched; and mechanism operating to secure a uniform stitch-length regardless of the length of stroke of the fulling feed-

30 member.

A further object of the invention is to provide a machine which will trim the edges of the material and present them in strictly abutted relation to the stitch-forming mech-

35 anism while avoiding an over-crowding of said abutted edges which, heretofore, has resulted in a seam somewhat bulky or ridged along the center line.

40 A further object of the invention is to provide a machine with trimming mechanism and covering thread laying mechanism constructed and arranged to relieve the presser-foot and bar of unnatural strains and to secure a maximum of space in rear

45 of the stitching point, thereby accommodat- ing a maximum accumulation of work about the arm.

50 Still further, the invention has for an object to overcome in a large measure the ob- jectionable effects caused by the inertia and

stretching tendency of the looper-thread as it is being rapidly and alternately paid out and taken up during the advance and retreat of the looper.

55 Further objects of the invention will appear from the following description and claims.

The present improvements are preferably embodied in a four-needle single-looper machine of the feed-up-the-arm type adapted 60 to produce a seam such as disclosed in the patent to Munsing No. 506,524, October 10, 1893; an additional needle being added in

the present instance, to form an additional row of stitches. The needle-thread control- 65

ing mechanism includes a series of thread-cams adapted to act on the needle-threads directly, instead of through cam-controlled thread-arms, thereby securing a positive action upon the needle-threads and avoiding 70 the noise and sluggishness of operation incident to the use of said thread-arms. In the present instance the thread-cams are specially shaped to closely and differentially control the needle-threads, as will be here- 75

inafter explained, to meet the exacting

thread-control requirements of a multiple- 80

needle single-looper machine of the present

character.

A feature of the present machine is the 85 work-arm which is sector-shaped in cross-section and within which the looper-shaft and differential feed are incorporated. In multiple-needle machines having the usual short-radius looper there is a great tend- 90

ency for the needle-loops to crowd together on the looper rather than remain properly spaced apart to permit the passage of the needles to one side of their respective loops.

95 By virtue of the present construction the longest possible radius of oscillation of the looper is provided, consistent with a given minimum circumference of the work-arm.

In addition to the long-radius looper the machine may be fitted with loop-detainers 100 one of which holds back on the looper-blade the first loop entered by the looper, so that said loop can not possibly slip forwardly and into the path of its corresponding needle during the loop-shedding stroke of the 105 looper. The remaining loop-detainers hold their respective loops forwardly on the looper-blade and prevent said loops from being dragged back into the paths of adjacent needles by the retracting looper.

110

While these loop-detainers are not generally essential to the practical operation of the present stitch-forming mechanism, their use under special conditions may sometimes 5 be deemed desirable.

The feeding mechanism is of the differential type represented in the application of G. E. Molyneux Serial No. 32,269, filed July 5, 1915, although differing therefrom 10 in certain important particulars. In the present instance the main and auxiliary feed-dogs are adjustably connected to their actuating means in such a manner that, in all positions of adjustment, the auxiliary 15 feed-dog will always assume the same definite position, relatively to the needles, at the end of its feeding stroke, preferably with its last tooth slightly in advance of the stitching point, while the main feed-dog will 20 always assume the same definite position at the beginning of its feeding stroke, preferably with its first tooth in the position previously occupied by the last tooth of the auxiliary feed-dog. Additional adjustments 25 of the feed-dogs, relatively to their feed-bars, are provided for varying the above defined positions of the feed-dogs relatively to the stitching point.

The machine is, in the present instance, 30 equipped with a presser-foot having a pivoted sole-portion cooperating with the feed-dogs and including spaced toes between which the upturned marginal portions of material are adapted to be presented and 35 fed toward the stitching point. The trimming mechanism of the present machine includes cooperative shearing blades adapted to operate directly above the space between the toes of the presser-foot. The lower or 40 ledger-blade is mounted independently of the presser-foot and is adapted to rise and fall with the latter. The cutter-blade is also mounted for rising and falling movements and is spring-pressed against the ledger-blade; being carried by an oscillating lever 45 fulcrumed on the bracket-arm independently of the presser-bar.

To avoid the production of a bulky or 50 ridged seam due to an overcrowding of the marginal portions of the trimmed material as it is pressed down by the presser-foot after leaving the trimming mechanism, the throat-plate of the present machine is provided with an inverted V-shaped ridged 55 member whose crest extends in a direction substantially parallel to the line of feed and against the oppositely inclined sides of which the material is pressed by correspondingly inclined under surfaces formed at the 60 inner edges of the presser-foot toes. Thus, the width of fabric remaining within the range of the needles is materially reduced and, as a result, an absolutely flat seam is produced. A suitable trimming guide is 65 provided to deflect the trimmings and is

mounted on the bracket-arm to swing outwardly to an inoperative position facilitating threading of the needles and cover-thread fingers. The trimming guide is connected with the presser-bar independently 70 of the presser-foot, to rise and fall with the latter.

In the accompanying drawings, Fig. 1 is a right side elevation of the machine, partly in section. Fig. 2 is a similar view from 75 the left side of the machine. Fig. 3 is a top plan view of the machine with the inclined driving shaft for the take-up cams omitted. Fig. 4 is a horizontal section through the standard above the plane of 80 the work-arm and showing the work-arm in plan. Fig. 5 is a front elevation of the machine with the looper enclosing end-cap in section. Fig. 5^a is a front elevation of the supporting frame and clamping devices 85 for the stripper plates used in connection with the upper thread-controlling cams. Fig. 6 is a rear end elevation of the machine partly in section to expose the mechanism housed within the standard. Fig. 6^a is a 90 cross-section through the tension-supporting frame illustrated in Fig. 6. Fig. 7 is an enlarged plan view of the free end portion of the work-arm. Fig. 8 is a cross-section 95 through the take-up supporting frame. Fig. 9 is a perspective view of a detail of the looper-actuating mechanism. Figs. 10 and 11 are cross-sections through the work-arm on the lines 10—10 and 11—11, respectively, Fig. 4. Fig. 12 is a vertical transverse section 100 through the throat-plate on the line 12—12 of Fig. 13. Fig. 13 is a bottom plan view of the throat-plate showing the loop-detainers carried thereby. Fig. 14 is a transverse vertical section through the throat-plate and presser-foot with the work in position therebetween and showing the relation of the trimmer-blades to the ridged work-supporting member carried by the 105 throat-plate. Fig. 15 is a plan view of the 110 mechanism carried by the bracket-arm adjacent the stitching point. Fig. 16 is a perspective view of the same with the work in position. Fig. 16^a is a vertical section 115 taken in a plane passing through the axis of the lower section of the presser-bar shown in Fig. 16. Figs. 17 and 18 are perspective views of the mechanism at the under side of the throat-plate showing the cooperation 120 of the looper and needle-loop detainers. Fig. 19 is a top plan view illustrating the cooperative relation of the needles, looper, needle-loops, and needle-loop detainers. Fig. 20 is a vertical longitudinal section on the line 20—20, Fig. 19, with the throat-plate 125 and material added. Fig. 21 is a similar view on the line 21—21, Fig. 19. Figs. 22 and 23 are side elevations of the feeding mechanism at the ending and beginning 130 points, respectively, of a feeding stroke.

Fig. 24 is an enlarged view illustrating the respective shapes of the take-up and thread-controlling cams mounted on the bracket-arm and Fig. 25 is a perspective view of the 5 seam produced by the machine.

The improvements are shown applied to a machine having a base 1 from which rises the standard 2 carrying the overhanging bracket-arm 3 terminating in the hollow 10 head 4. Secured to the standard 2 is the flanged rearward extremity of the tubular work-supporting arm 5 which is formed with two angularly arranged flat sides 6, 7 (Figs. 10 and 11) and a curved upper side 8, where- 15 by said work-arm is substantially sector-shaped in cross-section. Secured to the front or free end of the work-arm casting is the throat-plate 9 whose opposite lateral edges are grooved at 10 to slidably receive and 20 support the end cap 11 which is sector-shaped at its rearward end to conform to the cross-sectional shape of the work-arm. The under surface of the end cap tapers upwardly and the sides thereof taper for- 25 wardly toward the free end of the throat-plate, as shown in Figs. 1 and 7, to facilitate the advance of tubular work about the work-arm and toward the stitch-forming mechanism. Journaled in and crosswise 30 of the standard 2, above the horizontal plane of the work-arm and crosswise of the vertical plane of the work-arm, is the main shaft 12 carrying a pulley wheel 13 and handwheel 14 both cast integral with a com- 35 mon hub 15.

The main-shaft is formed with a ball-crank 16 which is embraced by the lower strapped end of a pitman 17 the upper strapped end of which embraces a ball-ended 40 crank-pin 18 carried by the crank-arm 18' at the rear end of the needle-actuating rock-shaft 19 which is journaled within the bracket-arm 3 and, at its forward end, carries a crank-arm 20 connected to the re- 45 ciprocating needle-bar 21 by means of the link 22. Secured to the lower end of the needle-bar 21 is the needle-clamp-block 23 which, in the present instance, is socketed to receive four needles n^1 , n^2 , n^3 and n^4 ar- 50 ranged in a vertical plane transversely of the work-arm 5.

Mounted within the end cap 11, in cooperative relation with the needles, is the thread-carrying looper 24; the upper edge 55 of the blade of which is curved concentrically with the curved upper side of the work-arm, Fig. 5, while the lower edge 24' of said blade is but slightly curved or may even be substantially straight throughout a 60 portion of its length. The slotted shank of the looper is secured to the looper-support 25 by a screw 26 permitting adjustment of the looper-blade toward and from the stitching plane. The looper-support is 65 clamped to the front end of the oscillating

and endwise movable looper-shaft 27 which is journaled within and lengthwise of the work-arm 5 as closely as practicable to the apex of the angle formed by the flat sides 6 and 7 thereof, Figs. 10 and 11, said angle 70 being large enough to accommodate the necessary loop-seizing and -shedding strokes of the looper. It will be understood that this arrangement affords the longest possible radius of oscillation of the looper-blade for a 75 given circumference of the work-arm. In machines of the present character the circumference of the work-arm is limited by the size of the smallest tubular articles to be stitched and, in multiple-needle single- 80 looper machines, the longer the radius of oscillation of the looper-blade the greater the degree of certainty with which the needle-loops will be seized and maintained evenly spaced apart on the looper, as is es- 85 sential to the formation of a seam of the present character, since the needles in their descent must pass their respective previously formed loops without catching or splitting the threads thereof. 90

It will be seen by referring to Figs. 5 and 12 that the needle-eyes are arranged on an incline; being placed at progressively lower elevations beginning with the needle n^1 to compensate for the upward movement 95 of the needles as the looper-beak advances across the space between said needles; the purpose being to insure the passage of the looper-beak at the correct distance above each needle-eye to insure seizure of the re- 100 spective needle-loop. It will be further seen by referring to Fig. 5 that the needle points are arranged substantially in a common plane parallel to the plane of the throat-plate; the purpose being to insure that the 105 previously formed needle-loops on the looper will be passed simultaneously by their respective needles at the time the lower edge 24' of the looper-blade occupies a substan- 110 tially horizontal or otherwise favorable angular position relatively to the throat-plate.

The looper-shaft 27 carries at its rearward end a crank-arm 28 having a ball-crank-pin 29 which is embraced by the lower strapped end of a link 30 the upper strapped 115 end of which embraces a ball-eccentric 31 on the main-shaft 12 which imparts loop-seizing and -shedding movements to the looper. The hub of the crank-arm 28 is formed with a rearward extension carrying 120 a ball-ended pin 28' disposed concentrically with the axis of the looper-shaft and embraced by the socketed end of a link 32 whose opposite end is connected to the de- 125 pending arm 33 of a rock-lever fulcrumed to oscillate upon and independently of the cross-shaft 34 journaled in the standard 2. The upwardly extending arm 35 of said rock-lever is slotted at 36 to receive an adjustable pin 37 which, through the pitman 130

38, connects said lever with the eccentric 39 carried by the main-shaft; said eccentric serving to impart sidewise or "needle-avoiding" movements to the looper.

5 The feeding mechanism is as follows: secured to the main-shaft is the feed-advancing eccentric 40 which is connected by the pitman 41 to the rocker-arm 42 the split hub 43 of which is clamped to the cross-shaft 34 to which shaft is also clamped the split hubs of the main feed-advancing rocker-arm 44 and the auxiliary feed-advancing rocker-arm 45. The rocker-arm 44 is formed with a curved slot 46 in which is 10 adjustably secured a pin 47 connected to one end of a link 48 the opposite end of which is pivotally connected to a lever 49 depending from a fixed fulcrum-pin 50 which extends across and within the stand- 15 ard 2 in parallelism with the main-shaft 12. The lower end of the lever 49 is pivotally connected to the rearward end of the main feed-bar 51 which extends within and longitudinally of the work-arm and, at its 20 forward end, carries a screw-pin 52, Fig. 4, which passes through the slotted shank 53 of the main feed-dog 54 and serves to secure the latter to said bar while permitting adjustment of the feed-dog lengthwise of said 25 bar. When the main feed-dog is at the forward end of its stroke, Fig. 23, the slot 46 assumes a position concentric with the point of pivotal connection between the link 48 and the lever 49 so that the main feed-dog 30 will always assume the same forward position regardless of the position of adjustment of the pin 47 in the slot 46. The main feed-dog 54 is preferably so adjusted on the main feed-bar that the front tooth of said 35 feed-dog will rise into engagement with the fabric in a position somewhat in advance of the needles, as shown in Fig. 23.

The auxiliary feed-rocker 45 is formed with a curved slot 55 in which is fitted a pin 56 carried by the rear end of a link 57 the front end of which is pivotally connected to a lever 58 depending from the fulcrum-pin 50. The lower end of the lever 58 is pivotally connected to one end of a link-section 59, the opposite end of which carries a fixed pin 60 and a screw 61, both extending through the slot 62 in the rear end of the link-section 63, the front end of which is pivotally connected at 64 to a bracket 65 screwed to the side of the auxiliary feed-bar 66 which is deeply recessed or grooved at its under side, Fig. 11, to fit about and slide upon the forward end-portion of the main feed-bar 51. The feed-bar 66 carries the auxiliary feed-dog 67. When the auxiliary feed-dog 67 is at the rear end of its stroke, Fig. 22, the curved slot 55 is substantially concentric with the pivotal connection between the link 57 and lever 58 and, as a result, the auxiliary feed-dog will always assume the same

position relatively to the needles at the end of its feeding stroke, regardless of the position of adjustment of the pin 56. Preferably the link-sections 59 and 63 are so adjusted that the rear tooth of the auxiliary feed-dog will end its feeding stroke at the same position, somewhat in advance of the needles, at which the front tooth of the main feed-dog begins its feeding stroke. Thus, a uniform stitch-length will be secured regardless of the degree of fulling action of the auxiliary feed-dog. 70 75

The fulling feed may be readily adjusted while the machine is in operation by means of the treadle-controlled lever-arm 68 which is mounted on the rock-shaft 69 fulcrumed in the standard 2 and carrying a lever-arm 68' which is connected by the link 70 to the link 57. Adjustable stop-screws 71 and 72 are provided to limit the range of movement of the lever-arm 68 and a spring 73 connected to the lever-arm 68' and to the frame serves to return the parts to normal position when pressure upon the treadle is released. 80 85

The main and auxiliary feed-bars are supported within the work-arm on a fulcrum-block 74 which is fitted within the slot 75 in the main feed-bar and is carried by the fulcrum-pin 76, supported, in turn, at the forward end of the feed-lifting lever 77 which is pivoted within the work-arm on the trunnion-screws 78, 78. The said lifting lever 77 is rocked by means of the eccentric 78' carried by the main-shaft and embraced by the upper strapped end of a pitman 79 the lower end of which is pivotally connected to a rearward extension of said feed-lifting lever. 90 95 100

The feed-dogs cooperate with a presser-foot comprising, in the present instance, a sole-piece 80, Fig. 1, pivoted at 81 to the shank 82 secured to the lower end of the presser-bar 83 which is formed in two parallel sections offset from one another and connected to move as one bar by means of the lateral arm 84. The lower section of the presser-bar is journaled in the bushing 85 and bearing lug 86, Fig. 1, and the upper section is journaled in alined bearings formed on the bearing lug 87, Fig. 5, and in the top of the head 4. The presser-bar carries a bracket 88 extending laterally through a slot 89 in the head 4 and acted upon by a leaf spring 90 the pressure of which may be adjusted by means of the screw 91. The presser-foot may be lifted by means of the usual treadle-controlled lever 88' the forward extremity of which extends under the bracket 88. The sole-piece of the presser-foot is formed with forwardly extending spaced toes 92, Figs. 15 and 16, defining a slot within which the upturned portions of material to be stitched pass toward the stitching point.

The machine is provided with trimming mechanism comprising, in the present in- 130

stance, ledger and cutter-blades 93 and 94, respectively, which operate in advance of the stitch-forming mechanism to shear off the upturned portions of material. The ledger-blade rests in a groove 93' in the upper side of the left-hand presser-foot toe 92 and is rigidly clamped to the lower end of a vertically slideable rod 95 journaled in spaced lugs 96 formed on the bracket 97 secured to 10 and depending from the side of the head 4.

The cutter-blade 94 rests upon the ledger-blade and is clamped to the lower end of the vertically slideable rod 95 journaled in spaced lugs 99 formed at the forward end of the 15 cutter-lever arm 100 which is fulcrumed on the headed pin 101 fixed to and depending vertically from the bracket-arm 3 at a point closely in rear of the head 4. The other arm 102 of the cutter-lever is forked at its extremity to embrace a block 103 carried by the crank-pin 104 secured to the crank-disk 105 on the vertical shaft 106 which is rocked through a bevel-gear connection 107 with the needle-actuating rock-shaft 19. The cutter-blade slide-rod 98 is prevented from turning 20 in its bearing lugs by means of the collar 108, Fig. 15, secured thereto and slotted at 109 to embrace vertical guide-walls 110 formed at opposite sides of the vertical extension 100' at the front end of the lever-arm 100. A spring 111 surrounding the slide-rod 98 and interposed between the collar 108 and upper bearing lug 99 serves to 25 press the cutter-blade against the ledger-blade and maintain the latter in its groove in the presser-foot.

A collar 112, similar to the collar 108 is secured to the ledger-blade carrying rod 95 and cooperates with guide-walls on the 40 bracket 97 to prevent turning of the rod 95. This collar may, if desired, be adjusted downwardly sufficiently to maintain the ledger-blade at any desired elevation above the bottom of its groove in the presser-foot, 45 as will be readily understood. Thus, while the trimming blades are mounted to move up and down with the presser-foot they may also be adjusted to act at a fixed elevation independently of the presser-foot and, furthermore, the presser-foot does not have to resist the cutting thrust of the cutting blade, which in prior constructions tends to 50 twist or strain the presser-foot laterally or impart other unnatural strains to the presser-foot.

The trimmings are deflected to one side of the work-arm and prevented from interfering with the action of the parts adjacent the stitching point by means of the trimming guide 116 comprising a trough shaped member set on its side and having a receiving end cut to fit closely over the trimmer-blades, as shown in Fig. 16. The trimming guide 116 is carried at the lower end of the rod 117 journaled in a bearing lug 118 formed on the

guide-bracket 97. The rod 117 sustains at its upper end a laterally projecting finger-piece 119 which normally extends through a slot 120 in the side-wall of the bearing lug 118 and locks the trimming guide in operative 70 position. By lifting the finger-piece out of the slot 120 the trimming guide may be elevated and may then be turned laterally to inoperative position; the finger-piece 119 then resting upon the upper end of the bearing lug 118, as shown in Figs. 5 and 15. The coiled spring 121, Fig. 2, surrounding the reduced upper portion of the rod 117, within the bearing lug 118, presses said rod downwardly and yieldingly maintains the finger-piece 119 in engagement with the lower sleeved extremity of the adjustable link 122 depending from the bracket 88 carried by the presser-bar. By means of this connection the trimming guide will be caused to move 80 up-and-down in unison with the presser-foot but will not press downwardly against the latter or interfere with the tilting of the sole-piece 80. Further than this, an upward movement of the presser-foot will not tend 85 to twist or strain the trimming guide or cramp the supporting rod 117 in its bearings, as would be the case if the free end of the trimming guide rested upon the presser-foot.

In prior machines of the present character 90 the work has been sharply bent upwardly about the lower inner corners of the presser-foot toes and, when trimmed, an excess of vertically extending material remains below the plane of action of the trimmer-blades to 95 be pressed downwardly and incorporated in the seam. This results in an overcrowding of the material within the seam making it bulky or ridged along the center line. To avoid this overcrowding of the material and 100 facilitate the production of a perfectly flat seam, the throat-plate of the present machine is fitted with a narrow and elongated ridged member 123 whose crest 124 is disposed centrally of and parallel with the line 105 of seam formation and within the space between the presser-toes 92, Figs. 5 and 14; the under surfaces of said toes being inclined at their inner edges to correspond or coact with the inclined sides of the ridged member 123 110 which, it will be noted, extends beneath the trimming knives 93, 94, and supports the material at the point where it is being acted upon by said knives, thereby insuring that the edge portions of material will be supported in the desired inclined position at 115 the trimming point. It will be readily understood that this construction materially reduces the amount of material to be subsequently flattened and stitched. In the present instance, as the cut edge-portions of material leave the trimmer they travel down the inclined rearward end 125, Fig. 7, of the ridged member and are directed into abutting 120 relation in the plane of the work by the 130

cross-bar 126, Fig. 15, of the presser-foot without being unduly overcrowded.

- The covering threads to be incorporated in the upper side of the seam are presented by 5 a pair of eyed thread-fingers having curved horizontally disposed blades 127 and vertically arranged shanks 128; the latter being secured in socketed bosses 129 at the free ends of the thread-finger carrying levers 130 10 the opposite apertured ends of which are fulcrumed upon the lower reduced end of the bushing or sleeve 85 surrounding the presser-bar, as shown in Fig. 16^a. The thread-finger blades are preferably curved 15 to the same radius concentrically with the presser-bar and operate in planes one slightly above the other. Simultaneous oscillatory movements in opposite directions are imparted to the levers 130 by means of the links 20 131 which connect the latter with one arm of the bellcrank lever 132 fulcrumed on the headed pin 133 carried by the head 4. The other arm of the bellcrank lever carries a ball-ended pin 132' which is connected by a link 133' to a ball-ended pin 134' carried by the lower end of the depending arm 134 clamped to the front end of the rock-shaft 135 journaled at the side of the bracket-arm in the bearing lug 136. The rear end of the shaft 135 carries a crank-arm 137 which projects into the standard 2 through an opening 138 in the side of the latter and is connected by a ball-and-socket joint to the upper end of the pit-man 139 actuated by a ball-eccentric 140 on the hollow counter-shaft 141 journaled on the fixed pin 141' in parallelism with the main-shaft and driven by the latter through two-to-one speed-reducing gears 142. The 25 thread-fingers are thus actuated back-and-forth across the line of seam in front of the needles at one-half the frequency of reciprocation of the needles, so that each thread-finger presents its thread to the needles alternately at opposite sides of the line of seam. It will now be appreciated that when the trimming guide 116 is shifted to inoperative position the thread-fingers and needles will be exposed and may readily be threaded. 30 The take-up for the needle-threads consists of a thread-guiding bracket 143 secured to the top of the needle-bar 21 and formed with a horizontal bar having individual needle-thread eyes 144. Cooperating with 35 the take-up bracket 143 to differentially control the needle threads t^1 , t^2 , t^3 and t^4 are the respective thread-engaging cams c^1 , c^2 , c^3 and c^4 , each of which comprises, in the present instance, two similar spaced disks formed 40 integral with a common hub. Said cams are mounted on a cam-shaft 145 which is journaled in a thread-controller frame 146 secured to the top of the bracket-arm and is driven by a one-to-one bevel-gear connection 45 147 with the upper end of an inclined shaft

148 enclosed within the shaft casing 148'. The lower end of the shaft 148 is connected to the counter-shaft 141 by a one-to-two speed multiplying bevel-gear connection 149, whereby the shaft 145 is driven at the same 70 speed as the main-shaft 12. Rising from the frame 146 are two standards 150, Figs. 1 and 3, to each of which are pivoted the shanks of two similar fork-shaped thread-guides 151, the tines of each fork being disposed at opposite sides of a corresponding one of said thread-cams and apertured at 152 to guide the thread across the active peripheral portion of said cam. Threaded into the shank of each thread-guiding fork 75 151 is an adjusting screw 153 which determines the position or height of the thread eyes 152. A spring 154 presses against the inclined rear end of the shank of each fork and yieldingly maintains the screw 153 in 80 contact with the top-surface of the standard 150. One of the tines of each fork 151 is extended forwardly to form a finger-piece 155 which may be readily lifted by the operator to shift the fork to threading position, 85 shown in dotted lines, Fig. 1. Disposed in a plane between the spaced members of each thread-cam is a corresponding stripper-plate 156 the upper extremity of which is slotted at 157 to guide the thread and to cause said 90 cam to deflect the thread radially, thereby overcoming the tendency of the cam to carry the thread around with it. The shanks 156' of the stripper-plates 156 are fitted in corresponding slots cut in the supporting block 100 or frame 156'' and defining spaced and opposed abutments 156''' against which the shanks 156' are clamped by means of the arched springs 156^a through the centers of which pass the screws 156^b; said screws serving to slightly flatten the springs 156^a and thereby clamp the shanks of the stripper-plates 156 tightly against the abutments 156''', as will be readily understood. 105

Cooperating with the thread-cams are a 110 series of thread-nippers n , one for each thread. As these nippers are all alike a description of one will suffice. Referring to Fig. 8 it will be seen that each thread-nipper comprises a sleeve 158 which is fixed in 115 a socket in an upward extension 157 on the thread-controller frame 146. Fixed within the sleeve 158 is the shank of a headed pin 160 which nips and locks the thread against the top of said sleeve 158 under the influence 120 of the relatively strong coiled spring 161. The spring 161 surrounds the pin 160 and reacts against a shoulder within the sleeve 158 and an opposed shoulder within a smaller sleeve 162 telescoping within the 125 sleeve 158 and sustained by a cross-pin 163 extending through the pin 160. Journaled in the frame 146 at the lower ends of the pins 160 is a rock-shaft 164 which is cut away under each of said pins to afford a 130

lifting shoulder 164'. The rock-shaft 164 carries a crank-arm 165 which is pivotally connected to a pitman 166 actuated by the eccentric 167 on the shaft 145. The thread-nippers *r* act to lock and release the needle-threads during each cycle of operations, as will be more fully explained.

In addition to the needle-thread cams, the shaft 145 carries a covering thread-con-troller cam *c*⁵ and a covering thread pull-off cam *c*⁶. These cams and their cooperative thread-guides and stripper-plates are substantially of the same construction as the needle-thread cams and need no further de-scription. A plurality of superposed thread-nipper springs 168 are disposed between the thread-cams *c*⁵ and *c*⁶ and are actuated in the usual manner by the cam 169 on the shaft 145 to nip the covering threads during the action of the pull-off cam *c*⁶.

A series of guard-members or springs 170 are provided to prevent winding of the needle-thread about the take-up shaft 145 in case of thread-breakage. Each of the guard-springs is wide enough to extend across the space between adjacent cams and the ends of said springs may be fitted into suitable re-cesses provided therefor in the frame 146, as shown in Fig. 8.

Mounted on top of the bracket-arm at the rear of the machine is a tension-supporting frame 170* carrying a series of tensions 171 for the needle, looper and covering threads. Each of these tensions includes a tension-releasing pin 172: being of the well known construction disclosed, for example, in the patent to De Voe, No. 1,146,405. In the present instance, however, the pins 172 are lifted to release the tensions by shoulders 173 afforded by notches in the tension-releasing rock-shafts 175 journaled in the frame 170*. One of the rock-shafts 175 carries an arm 176 having a lateral pin 177 embraced by the forked extremity 178 of a lever 179 secured to the other rock-shaft 175 and actuated by means of a link connection 180 with the presser-foot lifting-lever 88'. When the presser-foot is lifted all the tensions 171 will, accordingly, be released.

The thread-engaging cams carried by the shaft 145 are shaped substantially as illus-trated in Fig. 24. Starting at the position shown, the needle-bar is at its highest point and the thread-nippers *r* are opened; the threads being restrained or steadied, how-ever, by the tensions 171. As the needles descend, the outwardly inclined portions of the cams to the left of the thread-eyes 152 positively take up or absorb the slack given up by the descending take-up guide-bar 143, thereby preventing the formation of slack thread below the needle-eyes and maintain-ing the previous needle-loops snugly about the looper-blade.

The eye of the needle *n*⁴ enters the work

as the thread-nippers *r* act to lock the needle-threads and as the peak *u*⁴ of cam *c*⁴ passes the line of stationary thread-guides 152. The inward inclination of cam *c*⁴ following the peak *u*⁴ gives up the thread re-quired by the eye of needle *n*⁴ as it doubles its thread below the material. Similarly, at successively later stages, the peaks *u*³, *u*² and *u*¹ of the cams *c*³, *c*² and *c*¹, respectively, pass the guides 152 as the eyes of needles *n*³, *n*² and *n*¹, respectively, descend below the work, and the inward inclines following said peaks give up the thread required by the respec-tive needle-eyes as they double their thread below the work.

At the point *v*⁴ the previously formed loop of the needle *n*⁴ is shed from the looper and the outward incline following the point *v*⁴ and leading to the peak *w*⁴ acts positively to quickly take up or tighten said loop. Similarly at the points *v*³, *v*² and *v*¹, the re-spective loops of needles *n*³, *n*² and *n*¹ are successively shed by the looper and are suc-cessively and positively tightened by the out-ward inclines following the points *v*³, *v*² and *v*¹ and leading to the respective peaks *w*³, *w*² and *w*¹. The inward inclines follow-ing said last-mentioned peaks give up the thread required by the needles to complete their down-strokes, while maintaining the previous needle-threads somewhat taut and closely under control.

When the needles reach the end of their down-stroke the cams have rotated 180° and the slight inward inclination of the cam *c*' following this point slightly slackens the thread *t*' so that the loop thrown out by the needle *n*' will not be robbed of any of its thread or reduced in size by the contract-ing tendency of the thread when relieved of strain. The progressively steeper outward inclines of the cams *c*², *c*³ and *c*⁴, following the 180° point, act to reduce the sizes of the respective loops presented by the needles *n*², *n*³ and *n*⁴, by drawing thread back through the eyes of said needles, to reduce said loops to the proper size prior to their seizure by the looper-beak. It will be under-stood that since the eye of the needle *n*⁴ descends below the work a greater distance than the needle *n*³ &c., more thread will have to be drawn back through the eye of the needle *n*⁴ than through the eye of the needle *n*³, etc., prior to seizure of the needle-loops on the looper, in order that said loops may be reduced to substantially the same size. The nippers *r* are opened as the needles start to rise.

When the peak *x*' reaches the line of thread-guide 152, the looper-beak will just have entered the loop of the needle *n*' and the inward inclination of the cam *c*', fol-lowing the peak *x*', will give up just enough thread to compensate for the take-up action of the needle-bar and maintain the loop of

needle n' snugly about the looper-blade. Similarly, as the peaks x^2 , x^3 and x^4 pass the guides 152 at successively later stages, the looper will have successively seized the 6 loops of the respective needles n^2 , n^3 and n^4 , and the inward inclines following said peaks will give up just enough thread to compensate for the take-up action of the rising needle-bar and maintain the loops of said 10 needles snugly about the looper-blade.

After the cams have rotated about 325° the last mentioned giving up action of the cams ceases and the continued upward movement of the needle-bar guides 144 acts to 15 draw or measure from the supply the amount of thread required for the next stitch; the nippers r being still open.

By these means the needle-threads are controlled in a positive and efficient manner 20 and a high-speed quiet running and quick acting system of differential thread-controllers is provided, thus insuring a full realization of the important advantages inherent in the idea of controlling the needle-threads 25 differentially as disclosed in said Molyneux and Gatchell application Serial No. 40,564.

By the use of a long radius looper in conjunction with the present thread-controlling mechanism, the needle-loops on the looper 30 will ordinarily be maintained evenly spaced apart so that each needle in its descent will pass down beside its respective previously formed loop. However, to further insure against abnormal displacement of the 35 needle-loops on the looper, the machine may, if desired, be equipped with the loop-detainers comprising, in the present instance, three hooked fingers 181 for cooperation with the loops of the needles n^2 , n^3 and n^4 and an 40 additional oppositely hooked finger 182 for cooperation with the loop of the needle n' . The detainers 181 are formed at the end of a plate 183, the slotted shank of which is entered by a screw 184 securing the shank 45 of said plate within a groove 185 at the under side of the throat-plate, thereby permitting adjustment of said fingers lengthwise of the throat-plate and facilitating accurate positioning of said fingers relatively to 50 the needles and looper.

The tip ends of the detainers 183 are curved or inclined opposite to the direction of retraction of the looper and are positioned between the needle-paths and above the 55 looper-path to engage the upper limbs of the respective previously formed needle-loops extending between the last stitch and the curved upper edge of the looper-blade, as shown in Figs. 20 and 21 and prevent the 60 retracting looper from dragging said loops back into the paths of their respective next adjacent needles. In practice, it is found that there is a tendency for the previously formed loop of the needle n' to slip toward 65 the point of the looper and into the path of

said needle. To avoid this difficulty, the looper-blade may be notched to provide a shoulder 186 adapted to engage the loop of said needle n' during the first part of the retracting stroke of the looper, as shown in 70 Fig. 17, and drag said loop backwardly a slight distance past said finger 182, the looper at the same time also moving sidewise under said finger, whereupon the loop slips over the shoulder 186 and is detained at one 75 side of the path of the needle n' by said finger, as shown in Figs. 19 and 20. The tip end of the finger 182 is preferably curved or directed slightly toward the direction of retraction of the looper-blade and is made 80 separately from the detainers 181 being, in the present instance, secured to the plate 183 by a screw 187 which permits adjustment of the finger 182 about said screw as a pivot.

The machine is provided with means controlled by the thickness of the work for regulating the amount of thread measured from the supply by the thread-eyes 144. Rising from the top of the head 4 is a post 190 carrying a pivot-screw 191 upon which 90 is fulcrumed the lever 192, the rearwardly extending arm of which is provided with a slot 193 entered by a lateral pin 194 adjustably secured in the horizontal slot 195 formed in the bracket 196 having an apertured hub surrounding and fixed to the presser-bar. The forwardly extending arm of the lever 192 is apertured at its free end to receive and support a horizontal thread-engaging rod 197 having a down-turned extremity 198. The rod 197 is disposed closely in rear of the plane of reciprocation of the take-up eyes 144 and arrests the upward movement of the needle-thread-lengths extending forwardly from the thread-guiding 100 forks 191 and causes the thread-eyes 144 to pull an amount of thread from the supply depending upon the elevation of the rod 197. If the work increases in thickness the rod 197 will be lowered and consequently 110 will arrest the upward movement of the needle-threads earlier and increase the pull-off action of the thread-guides 144, accordingly, as will be clear from an inspection of Fig. 1.

Journalized within and crosswise of the rearward end of the worm-arm 5 is a shaft 199 which is connected to the gear 142 on the hollow counter-shaft 141 by a gear 200 of one-half the size of the gear 142 in 120 order that the shaft 199 will be driven at the same speed as the main-shaft 12. Mounted upon the shaft 199 and within the work-arm is a looper-thread controller-cam 201, a looper-thread pull-off cam 202 and a 125 thread-nipper actuating cam 203.

The construction of the cams 201 and 202 is similar to that of the cams carried by the shaft 145; the cam 201 being shaped to control the slack in the looper-thread as 130

the looper advances and retreats while the cam 202 is shaped to measure off a supply of looper-thread required for the formation of a stitch. Cooperating with the cams 201 and 202 are thread-engaging forks 203 whose tines are apertured at 204 and whose shanks 205 are pivoted at 206 to brackets 207 mounted on lugs 208 within the work-arm. The thread guiding apertures 204 may be raised or lowered by means of adjusting screws 209 and the rearward inclined ends of the shanks 205 are acted upon by springs 210 to yieldingly maintain the screws 209 in contact with the brackets 207 while permitting the forks to be swung upwardly to threading position. Stripper wires 211, corresponding in function to the stripper-plates 156 previously described, are situated between the disks of each cam. The nipper-cam 203 acts upon a pair of superposed nipper-springs 212 to nip the looper-thread; the timing in the present instance being such that the nippers are closed upon the thread as the looper begins its retracting stroke, and are opened as soon as the advancing looper has entered all of the needle-loops. The pull-off cam 202 begins to pull looper-thread from the supply as soon as the nippers 212 are closed and gives up the thread to the advancing looper as soon as the nippers are opened. The incorporation of a rotary looper-thread controller within a hollow work-supporting arm is believed to be broadly new with me and it is an important improvement over prior devices of a similar nature for the reason that it is located nearer the stitching point and consequently will allow the relatively short length of thread extending forwardly to the looper to be rapidly and readily paid out and taken up exactly as required by the looper, as it alternately advances and retreats.

Having thus set forth the nature of the invention, what I claim herein is:—

1. A sewing machine comprising, in combination, a frame including a fixed work-support and an overhanging bracket-arm, a spring-pressed presser-bar journaled in said bracket-arm, a presser-foot carried by said presser-bar and having spaced toes between which upturned marginal portions of material are adapted to pass, and trimming mechanism mounted on said frame independently of said presser-foot and bar and including cooperating shearing elements adapted to trim off said up-turned portions of material.

2. A sewing machine comprising, in combination, a frame including an overhanging bracket-arm, a presser-bar, a presser-foot carried by said presser-bar and having spaced toes between which upturned marginal portions of material are adapted to pass, and trimming mechanism mounted on said frame independently of said presser-

foot and bar and including downwardly spring-pressed cooperative shearing elements resting upon said presser-foot and adapted to trim off said upturned marginal portions of material. 70

3. A sewing machine comprising, in combination, a frame including an overhanging bracket-arm, a presser-bar, a presser-foot carried by said presser-bar and including a pivoted sole-portion formed with spaced toes between which upturned marginal portions of material are adapted to pass, and trimming mechanism mounted on said frame and including cooperative shearing elements adapted to trim off said upturned portions of material. 75

4. A sewing machine comprising, in combination, a frame including an overhanging bracket-arm, a spring-pressed presser-bar, a presser-foot carried thereby and including a pivoted sole-portion formed with spaced toes between which upturned marginal portions of material are adapted to pass, and downwardly spring-pressed trimming means adapted to rest upon the pivoted sole-portion of said presser-foot and trim off said upturned marginal portions of material. 80

5. A sewing machine comprising, in combination, a frame including an overhanging bracket-arm, stitch-forming mechanism including a reciprocating needle, a presser-foot including spaced toes between which upturned marginal portions of material are adapted to pass and be trimmed, a presser-bar supporting said presser-foot, a ledger-blade mounted on said frame independently of said presser-foot and bar and a reciprocating and downwardly spring-pressed cutter-blade resting upon said ledger-blade. 95

6. A sewing machine comprising, in combination, a frame including an overhanging bracket-arm, stitch-forming mechanism including a reciprocating needle, a spring-pressed presser-bar, a presser-foot carried thereby and including spaced toes between which upturned marginal portions of material are adapted to pass and be trimmed, a ledger-blade resting upon said presser-foot, a bar movably mounted upon said frame independently of said presser-bar and carrying said ledger-blade, and a reciprocating and downwardly spring-pressed cutter-blade resting upon said ledger-blade and yieldingly pressing the latter against said presser-foot. 105

7. A sewing machine comprising, in combination, a frame including an overhanging bracket-arm, stitch-forming mechanism including a reciprocating needle, a spring-pressed presser-bar, a presser-foot carried thereby and comprising a shank and a pivoted sole-portion formed with spaced toes between which upturned marginal portions of material are adapted to pass and be trimmed, a ledger-blade resting upon 120

125

130

8. A sewing machine comprising, in combination, fabric-uniting means, a work-supporting port having angularly related flat surfaces intersecting in an edge to form a ridge extending lengthwise of the line of seam-formation, presser-means adapted to press the work against the flat side surfaces of said ridge and including spaced portions defining a slot between which upturned marginal portions of material are adapted to pass, trimming mechanism disposed in advance of said fabric-uniting means and adapted to trim off said upturned marginal portions of material, and means for pressing the trimmed edge portions of material into abutting relation before they are united.
9. A sewing machine comprising, in combination, a frame, covering stitch-forming mechanism incorporated in said frame, feeding mechanism including a feed-dog, presser means opposed thereto and including spaced work-engaging toes between which upturned marginal portions of material are adapted to pass toward the stitching point, a work-support having angularly arranged flat surfaces intersecting in an edge and forming an inverted V-shaped ridge having a crest which extends lengthwise and substantially centrally of the line of seam and is disposed within the space between said toes, the work-engaging surfaces of said toes being inclined to correspond with the complementary work-engaging surface portions of said ridge, trimming mechanism including a cutting device operating close to said presser-foot and above said ridge, and means for directing the cut edges into abutting relation.
10. In a sewing machine, in combination, stitch-forming mechanism, feeding mechanism comprising laterally spaced feed-dog sections, presser means including spaced toes opposed to said feed-dog sections, a throat-plate having a substantially flat surface adjacent the stitching point and formed in advance thereof with a ridge presenting oppositely inclined sides defining planes meeting in an apex extending in the direction of feed substantially centrally of the line of seam and disposed above the throat-plate and within the space between said toes, trimming mechanism including knives adapted to operate on the fabric in advance of the stitch-forming mechanism at a point where the fabric is supported by said ridge, and means for directing the cut edges into abutting relation.
11. In a sewing machine, in combination, multiple needle seam-covering mechanism, a throat-plate having a flat work-supporting surface surrounding the stitching point and a ridged work-supporting surface having angularly related flat sides intersecting in an edge in advance of the stitching point and above the level of said flat work-supporting surface, feeding mechanism comprising feed-dog sections disposed at opposite sides of said ridged work-supporting surface, a presser-foot having a flat heel-portion and spaced toe-portions cooperating with said feed-dog sections and having their inner lower corners beveled to conform to the flat sides of said ridged work-supporting surface, and trimming mechanism operating above said ridged work-supporting surface and adapted to trim off the upturned marginal portions of material passing between said toes, the heel-portion of the presser-foot operating to direct the cut edges into abutting relation.
12. A sewing machine having, in combination, stitch-forming mechanism including a plurality of reciprocating needles and a looper cooperating therewith to form stitches, horizontally acting trimming mechanism including an oscillatory trimmer blade adapted to act upon the work in advance of the needles and operating at the same frequency as the needles, and covering thread laying mechanism including a thread-finger movable back and forth across the line of seam in advance of the needles at half the frequency of reciprocation of the latter.
13. In a sewing machine, in combination, a frame, stitch-forming mechanism including a plurality of reciprocating needles and complementary loop-taking means, a presser-bar, a presser-foot having spaced toes between which upturned marginal portions of material are adapted to pass, trimming mechanism including an oscillatory blade operating at the frequency of reciprocation of the needles and adapted to trim off said upturned marginal portions of material, and an oscillating covering thread finger having a thread delivering eye moving back and forth across the line of seam in front of the needle at half the frequency of reciprocation of the latter and journaled concentrically with but independently of the presser-bar.
14. In a sewing machine, in combination, stitch-forming mechanism including a plurality of reciprocating needles and complementary loop-taking means, a presser-bar, a presser-foot having spaced toes between which upturned marginal portions of material are adapted to pass, trimming mechanism including an oscillatory blade operating at the frequency of reciprocation of the needles and adapted to trim off said up-

- turned marginal portions of material, and a pair of oscillating covering thread-fingers journaled concentrically with the presser-bar and having their lower end-portions 5 curved to the same radius concentric with the presser-bar and disposed in horizontal planes, said fingers being formed with thread delivering eyes adapted to pass back-and-forth across the line of seam in front of 10 the needles at half the frequency of reciprocation of the latter.
15. In a sewing machine, in combination, a presser-foot having spaced toe-portions, presser-foot lifting means, trimming mechanism adapted to trim off upturned marginal portions of material passing into the space 15 between said toe-portions, a trimming guide, and connections between said presser-foot lifter and said trimming guide, independent 20 of said presser-foot, for lifting said guide.
16. In a sewing machine, in combination, a presser-bar, a slotted presser-foot secured thereto, trimming mechanism adapted to trim off upturned marginal portions of material 25 passing into the slot of said presser-foot and a vertically movable trimming guide sustained by said presser-bar independently of said presser-foot.
17. In a sewing machine, in combination, 30 an over-hanging bracket-arm, a head sustained at the free end of said arm, a slotted presser-foot mounted in said head for rising and falling movements, a depending bracket secured to one side of said head, a ledger-blade mounted in said bracket for rising and 35 falling movements, a trimming guide mounted in said bracket for rising and falling and lateral turning movements, and a trimmer-blade cooperating with said ledger-blade above the slot in said presser-foot to 40 trim off upturned marginal portions of the material in advance of the trimming guide.
18. A sewing machine having, in combination, stitch-forming mechanism, a spring-pressed presser-foot, and horizontally acting trimming means mounted for vertical adjustment to different operative levels independent of said presser-foot and operating upon the work in advance of the stitch-forming mechanism. 45
19. A sewing machine comprising, in combination, covering-stitch-forming mechanism, feeding mechanism, a work-support having a ridge disposed lengthwise and substantially centrally of the line of seam 50 formation, spaced presser toes disposed over said ridge and defining a slot between which upturned marginal portions of material are adapted to pass, trimming mechanism in advance of said stitch-forming mechanism 55 and including a cutting device disposed directly over said ridge and operating to trim off the upturned marginal portions of material when supported by said ridge, and means for directing the trimmed edges into 60 abutting relation. 65

In testimony whereof, I have signed my name to this specification.

GEORGE S. GATCHELL.
